ATTORNEY.

UNITED STATES PATENT OFFICE.

FREDERICK F. OLAZABAL, OF LOS ANGELES, CALIFORNIA.

MAGAZINE HAMMER.

Application filed January 22, 1927. Serial No. 162,769.

This invention relates to hammers and more particularly to a magazine hammer for progressively driving a plurality of staples, nails or the like contained in the hammer's magazine.

The general object of the invention is to provide a magazine hammer of the character stated which will be simple in construction, practical and efficient in operation, easy to handle and operate and which may be easily and readily taken apart and assembled.

A more particular object is to provide a magazine hammer including a magnetic plunger for projecting and holding the staples or nails in position to be driven by the hammer.

Other objects and advantages will appear hereinafter.

The invention is illustrated in the annexed drawing which forms a part of this specification and in which

Fig. 1 is a side elevation of my magazine hammer.

Fig. 2 is a longitudinal section of the hammer taken on line 2—2 of Fig. 1.

Fig. 3 is a view partly in longitudinal section of the hammer taken on line 3—3 of Fig. 2.

Fig. 4 is a cross section of the hammer head taken on line 4—4 of Fig. 3.

Fig. 5 is a longitudinal section on line 5—5 of Fig. 1.

Fig. 6 is a cross section of the hammer handle and magazine taken on line 6—6 of Fig. 1.

Fig. 7 is a cross section of the hammer head taken on line 7—7 of Fig. 3.

Corresponding parts are designated by the same reference characters in all the figures.

In the drawing, 1 designates the head and 2 the handle of the hammer. The head 1 is made in three pieces, comprising a pair of substantially semi-cylindrical head members 3 and 4 and a cylindrical shell member 5 enclosing said head members, the head members being placed together with their inner flat faces 6 and 7 against each other. The shell member 5 is formed with a sleeve 8 at one side extending at right angles to the axis of the shell intermediate the ends of the shell and provided with an internal thread 9 in which sleeve the inner end of the handle is screw seated, said inner end of the handle being provided with a thread 10 for engaging the sleeve thread 9. Screws 11 extend through the shell member 5 and engage the

head member 3 to hold it in position in the shell member, while screws 12 extend through the shell member into the head member 4 to hold it in the shell member. The head member 3 is formed with a longitudinal slideway 13 in its inner flat face 6, the upper side of which slideway is closed by the inner face 7 of the member 4 in which slideway slides a plunger 14 on the rear end of which is pivoted a dog 15. The plunger 14 is a permanent magnet. The head 2 is also provided with a bore 16 in both of the members 3 and 4, and the member 3 has a groove 16^a at the rear side of the bore 16, which bore and groove extend inwardly from the top of the head to the upper end of the slideway 13. The groove 16^a communicates at its inner end with an opening 17 leading rearwardly through the member 3 to the inner end of a bore 18 which extends rearwardly through the wall of the sleeve 8. A wire 19 connected at one end to the dog 15 extends through the groove 16^a, opening 17 and bore 18 along the handle 2 through eye 20 on the handle near the outer end thereof, and the other end of the wire is connected to one end of an operating lever 21, which is pivoted to the handle at 22 and is formed with a handle 23 to be pressed inwardly by the two forefingers of the operator's hand which grasps the handle.

The head member 3 is provided with a bore 25 leading from the rear of the slideway 13 through the member and communicating with a bore 26 extending longitudinally in the handle 2 from the inner end to a point near the outer end of the handle forming a magazine 27 for the staples 28, or other articles to be driven. In the handle bore 26 is slidably mounted a plunger 29 formed with a lug 30 projecting through a slot 31 extending longitudinally in the handle outwardly from the bore 26. The outer end of the lug 30 is connected to one end of a spring 32 which extends along the hammer handle 2 and around the hammer head 1 and is connected at its other end to the head by a pin 33. The staples or other articles to be driven are placed in the magazine 27 and are pressed forwardly by the plunger 29 under the influence of the spring 32 so that the foremost staple is held against the inner flat face 7 of the head member 3 in the slideway 13 with the head of said staple facing the inner end of the plunger 14. A spring 34 surrounds the plunger 14 bearing at one end against a collar 14^a the upper end of the plunger and at

its other end against shoulders 35 in the head member at the inner end of the bore 16 which spring normally retracts the plunger so that its inner end rests adjacent to the head of the 5 foremost staple 28 in the slideway 13. In the inner flat face of the head member 4 is provided a recess 36.

In operation the user grasps the handle 2 and as he swings the same he presses the lever 10 handle 23, with his two foremost fingers, toward the hammer handle 2 until the plunger 14 is drawn downwardly by the wire 19, forcing the foremost staple through the slideway 13 out of the lower end of the hammer head, whereupon the dog 15 is swung into the recess 36 locking the plunger against backward movement until the staple 28 is driven by the hammer head 1 and plunger 14, the magnetism of the plunger holding the staple in position on the forward end of the plunger for driving. Upon releasing the lever 21 the spring 34 retracts the plunger 14 and the next foremost staple 28 in the magazine is forced forwardly into the slideway 13 by the plunger 14 under the influence of the spring 34.

Having described my invention, I claim:

1. In a hammer, a slideway extending through the lower end of the head of the hammer, a magazine for containing the articles to be driven, the forward end of said magazine communicating with the inner end of said slideway, means for feeding the articles from said magazine into the rear end of said

slideway, a plunger mounted to slide in said slideway, a spring for normally holding the plunger retracted above the article in the slideway at the forward end of the magazine, a dog pivoted on the upper end of said plunger, an operating lever on the handle of the hammer to be pressed by the hand of the operator while gripping the handle, and a wire connected at one end to said dog and at its other end to said lever for projecting said plunger forwardly when said lever is pressed to project an article through said slideway. 45

2. In a hammer, a slideway extending through the lower end of the head of the hammer, a magazine for containing the articles to be driven, the forward end of said magazine communicating with the inner end of said slideway, means for feeding the articles from said magazine into the rear end of said slideway, a plunger mounted to slide in said slideway, means for normally holding the plunger retracted above the article in the slideway at the forward end of the magazine, a dog pivoted on the upper end of said plunger, actuating means connected to said dog for projecting said plunger forwardly to project an article through said slideway, the head of the hammer being provided with a recess to receive the end of the dog to lock the plunger in its forward position for driving an article projected by the plunger. 55

FREDERICK F. OLAZABAL.
